UNITED STATES PATENT OFFICE.

FRANK W. WOOD, OF INDIANAPOLIS, INDIANA.

DESIGN FOR A WATCH-CHAIN.

SPECIFICATION forming part of Design No. 25,501, dated May 19, 1896.

Application filed March 18, 1896. Serial No. 583,816. Term of patent 3½ years.

To all whom it may concern:

Be it known that I, FRANK W. WOOD, a citizen of the United States, residing at Indianapolis, in the county of Marion and State of Indiana, have invented and produced a new and original Design for Watch-Chains; and I do hereby declare the following to be a full, clear, and exact description of the same, reference being had to the accompanying drawing, forming a part thereof.

In the accompanying drawing my new design for watch-chains is clearly shown, it consisting, essentially, of the links formed after the general style or form of a bicycle-chain and a charm of the form of a sprocket-wheel connected thereto, the leading or characteristic feature of the invention being the watch-chain of the unitary design, as shown in the drawing.

The chain shown is that style known as the "fob," and the sprocket-wheel constitutes the depending end; but, as will be readily

understood, this might be attached to any watch-chain in the same manner as is the ordinary "charm," or the length and style of the chain may be varied to suit different methods of using or different tastes without departing from the essential features of my design, which consists in a watch-chain embodying links of a style resembling bicycle-chain links in connection with a fob or charm of a form and style resembling a bicycle sprocket-wheel.

Having thus fully described my said design, what I claim as new, and desire to secure by Letters Patent, is—

The design for a watch-chain substantially as herein shown and described.

In testimony whereof I affix my signature in presence of two witnesses.

FRANK W. WOOD.
